TABLE FOR ENVELOPE-TREATING MACHINES

Commodore D. Ryan, Los Angeles, Calif., assignor to National Postal Meter Company, Inc., a corporation of Delaware

Application October 25, 1940, Serial No. 362,727

4 Claims. (Cl. 120—6)

This invention relates to machines for treating matter such as envelopes. Thus it is particularly useful in machines for sealing envelopes, printing postage on envelopes, printing addresses on envelopes, etc., although it also may be employed with machines for treating objects other than envelopes, such as slips of paper, or cardboard, etc.

A general object of the invention is to facilitate hand-feeding of envelopes and the like into a machine, one at a time.

A more specific object is to provide a table on a machine for treating envelopes, or the like, which table is simple and inexpensive, and yet at the same time facilitates the accurate and rapid hand-feeding of envelopes, or other articles one at a time.

Other more specific objects and features of the invention will become apparent from the following detailed description of a particular embodiment thereof, as illustrated in the drawing.

In large machines for printing or treating objects, such as envelopes, in large quantities, it is customary to provide a magazine into which a quantity of envelopes are placed by hand, with an automatic mechanism for feeding the envelopes from the magazine into the machine one at a time in rapid succession. However, there are a great many small printing machines adapted to handle such small quantities of matter that the provision of a magazine and an automatic feeding mechanism from the magazine is not justified. Heretofore, in operating such machines, it has been the practice for the operator to pick up envelopes, for example, one at a time, and feed them into the machine.

In accordance with the present invention, I provide a very simple supporting structure for small machines of the type described, which greatly simplifies and speeds up the manual feed of the envelopes into the machine.

In the drawing:

Fig. 1 is a plan view of that portion of an envelope-sealing and postage-printing machine into which envelopes are fed;

Fig. 2 is a front elevational view of the machine shown in Fig. 1;

Fig. 3 is a detail sectional view, taken in the plane III—III of Fig. 1; and

Fig. 4 is a detail sectional view, taken in the plane IV—IV of Fig. 1.

Referring to the drawing, there is disclosed a postage-printing machine which seals and prints postage onto envelopes fed therethrough. It includes a table 1 which supports an envelope

5 in printing position between a printing head 2 positioned above the table 1 and a platen 3 positioned below the table. The details of the printing apparatus do not constitute a part of the present invention. Suffice it to say that envelopes are slid by hand from left to right along the table 1 into printing position between the printing head 2 and the platen 3.

The present invention relates to the construction of the table at a point to the left of the printing head 2, where a stack of envelopes is positioned and envelopes fed therefrom one at a time onto the table 1.

Thus, as shown to best advantage in Fig. 2, the table 1 merges at an upper edge 4 into the upper portion of an inclined plane 5, which in turn merges at its lower edge into a horizontal plate 6 positioned parallel to, but below, the level of the table 1.

20 The plate 6 is of sufficient length to support the leading ends of a stack of standard short envelopes, while the trailing ends overhang the plate 6 for ready support by the operator's left hand, as shown in Fig. 1. When feeding the envelopes into the machine, the operator lightly presses the stack of envelopes against the inclined plane 5 to cause the envelopes to shingle, thereby facilitating separation. The envelopes are fed one by one into the machine by stripping the top envelope from the stack with the operator's right-hand fingers, shown in Fig. 1, and sliding it along the table 1. This stripping is accomplished by virtue of the fact that the friction between the finger tips and the top envelope is greater than the friction between the top envelope and the next envelope therebelow.

35 The degree of effectiveness of the envelope stripping may be controlled within limits by varying the angle of inclination of the stack with respect to the inclined plane 5. The higher the left end of the stack, the greater the resistance to movement of the envelopes. As the stack diminishes, it may be raised up along the inclined plane 5 by pushing the stack bodily to the right. With a little practice, the operator quickly learns the best position and angle of the stack for rapid feeding of the envelopes, one at a time.

40 By virtue of the fact that the inclined plane 5 is straight, it exerts the same retarding influence on all of the envelopes.

45 There is incorporated in the machine shown in the drawings, a moistening device for moistening the gum on the flaps of the envelopes as they are fed from the stack onto the table 1.

50 Thus referring to Fig. 3, the inclined plane 5

consists of a sheet-metal member which is bent at its upper end to form an extension 7 level with the table 1 and tilted downwardly at its right end to form a lip 8. Similarly, the left end of the table 1 is tilted downwardly to form an inclined lip 9, and a moistening tongue 10 is positioned above the lips 8 and 9. This moistening tongue 10 is supported at its forward end on the table 1, as indicated in Fig. 4, and is connected through a fitting 11 and a tube 12 with a water reservoir, not shown. The tongue 10 has a narrow slit in its underside through which water seeps to moisten the gummed surface of an envelope flap passing thereunder.

Referring now to Fig. 1, envelopes are positioned in the stack with their flaps folded under the body of the envelope, and as the top envelope is moved off the stack up over the inclined plane 5, the flap is separated from the body of the envelope by a curved edge 15 of a vane 14. As shown to best advantage in Figs. 2 and 4, the front portion of the edge 15 of the vane 14 is bent downwardly to form a lip 16, resting against the table 1 immediately in back of the edge 4 so that the leading edge of the body of an envelope riding up over the edge 4 is guided onto the upper surface of the vane 14 and passes over the moistening tongue 10, as clearly illustrated in Fig. 3. However, the flap of the envelope is separated from the body by the curved edge 15 of the vane 14 and is guided below the moistening tongue 10 so that the gummed surface of the flap moves past the slit 13 through which water escapes to moisten the gum. The flap is later pressed against the envelope to cause it to adhere thereto, by pressure means which does not constitute a part of the present invention and will, therefore, not be described.

To guide the envelope in the desired path of travel relative to the flap-moistening structure and the printing mechanism, a vertical guide wall 18 is provided at the rear edge of the plate 6, the inclined plane 5, and the left end of the table 1. There is also, preferably, a spring finger 19 secured to the guide wall 18, the free end of which engages each envelope as it moves up over the edge 4 to hold it down to facilitate the entry of the edge 15 of the vane 14 between the envelope and its flap.

The number of envelopes that can be handled in one stack above the plate 6 depends upon the length of the straight portion of the inclined plane 5. Obviously if the stack is of such vertical dimensions that the second envelope from the top is positioned above the edge 4, then the force

restraining that envelope against feeding movement will be lessened, and there is an increased chance of its being fed into the machine simultaneously with the top envelope.

Although for the purpose of explaining the invention a specific embodiment thereof has been described in considerable detail, it is to be understood that the invention is not limited to the exact construction, but is limited only to the extent set forth in the appended claims.

I claim:

1. A table for supporting a series of flat objects to be successively treated by a machine, said table having an edge over which objects are fed onto the table, a straight inclined plane leading upwardly to and joined with said edge and defining therewith an abrupt corner, whereby a stack of objects can be supported at their front edges on said inclined plane and the top object slid off

20 the stack up along said inclined plane and onto and along said table.

2. A table for supporting a series of flat objects to be successively treated by a machine, said table having an edge over which objects are fed onto the table, an inclined plane leading upwardly to

25 and joined with said edge and defining therewith an abrupt corner, an auxiliary table positioned at an angle to said inclined plane and at a lower level than said first-mentioned table, said inclined plane merging into said auxiliary table.

3. A table for supporting a series of flat objects to be successively treated by a machine, said table having an edge over which objects are fed onto the table, an inclined plane leading upwardly to

30 and joined with said edge and defining therewith an abrupt corner, and guide means mounted above said table adjacent to said edge for holding objects down against said table as they are slid onto said table over said edge.

4. A table for supporting a series of flat objects to be successively treated by a machine, said table having an edge over which objects are fed onto the table, an inclined plane leading upwardly to

35 and joined with said edge and defining therewith an abrupt corner, an auxiliary table positioned at an angle to said inclined plane and at a lower level than said first-mentioned table said inclined plane merging into said auxiliary table, a vertical guide plate arranged at the rear

40 edges of said tables and said inclined plane, and a resilient depresser member secured to said vertical guide plate for pressing each envelope against said first-mentioned table as it is fed over said edge.
